UNITED STATES PATENT OFFICE.

JAMES H. DREW, OF ROCHESTER, MINNESOTA.

AIR-BRAKE SYSTEM.

Application filed August 5, 1920, Serial No. 401,320. Renewed July 21, 1922. Serial No. 576,629.

To all whom it may concern:

Be it known that I, JAMES H. DREW, a citizen of the United States, residing at Rochester, in the county of Olmsted and 5 State of Minnesota, have invented certain new and useful Improvements in Air-Brake Systems, of which the following is a specification.

The present invention relates to improvements in air brake systems designed primarily with a view to providing means for "cutting out" the brake actuating mechanism of a particular unit in a train at will.

It is well known that quite frequently the 15 brake mechanism of a car in a train for one reason or another becomes defective or temporarily inoperative, resulting in ineffective release of the brakes with consequent damage to the wheels, the stalling of the 20 train on inclines, or the loss of time while the brakeman is cutting out the car in the usual manner when the train has been brought to a stop.

The customary method for accomplishing 25 the latter, as premised, requires in the first place, that the train be stopped, and in the second place that the brakeman crawl beneath the particular car to manipulate the cut out valve which shuts off the pressure 30 in the train line, and then that he should open the drain cock on the auxiliary reservoir to bleed the latter.

The object of my invention, however, is 35 to provide a valve in the brake system which is arranged at a convenient point, either within or without the car so that whenever the car should be "cut out" this valve need only be turned to cut off the service to the triple valve and simultaneously bleed 40 the auxiliary reservoir to thereby release the brakes, this being capable of accomplishment either while the train is in operation or at a stand still.

With these and other objects in view the 45 invention consists in the novel combination and arrangement of parts as will be herein-after fully described and claimed.

Figure 1 is a view showing in side elevation the brake mechanism which is arranged 50 and constructed in accordance with my invention;

Figure 2 is a plan view of the system as shown in Fig. 1;

Figure 3 is a bottom plan of the release 55 valve forming the special feature of this invention;

Figure 4 is a top plan view of the same; Figure 5 is a vertical sectional view through the release valve showing the latter in exhaust position; and

Figure 6 is a horizontal sectional view through this valve.

Corresponding and like parts are referred to in the following description and indicated in all the view of the drawings by the same reference characters.

The majority of the details of the air brake system which is herein illustrated are of conventional form and need only be referred to generally in this description in conjunction with the arrangement forming the subject matter of my invention.

Referring to Fig. 2, A designates the train line or service pipe, B the auxiliary reservoir, C the brake cylinder, and D the triple valve. As is customary the triple valve is placed in communication with the service pipe A by the branch pipe E, but in this arrangement which I have devised I interpose a special valve F in this branch pipe E, said valve, however, being so arranged that it will be convenient of access from the car, either at a point within the same or exterior thereto as may be found desirable. In the majority of the well known systems which are standard quick action automatic brake systems, the auxiliary reservoir merely has a drain cock so as to enable this reservoir to be exhausted when the brake mechanism is to be disarranged or rendered inoperative. Instead of this drain cock in my arrangement I employ a branch pipe G leading from this auxiliary reservoir to the proper port of the release valve F so that by the simple operation of the valve F the pressure from the service pipe A to the triple valve may be discontinued or interrupted at the same time that the auxiliary reservoir is opened to atmosphere through the branch pipe G.

Referring now to Figs. 3 to 6 it will be observed that the branch pipe E for the triple valve enters at one side of the valve housing from the service pipe A, as indicated at E', and passes to the triple valve from the opposite side as indicated at E''. The auxiliary reservoir branch pipe G is connected with the valve F at another side as indicated at G', while the valve body or casing at the opposite side is provided with an exhaust port to atmosphere as shown at G''.

The valve construction of this release valve F is as follows:

The shell 1 is formed with a tapering bore in which is received a turning plug 2, the latter being insertable from the under side 5 when the screw cap 3 is removed. The latter is formed with a wrench hold 4 and an interior recess 5 in which is disposed a spring 6 adapted to press against the plug 2 to hold it firmly in place. At the top, the plug 2 is formed with an extension 7 upon which a handle 8 is removably connected by means of the pin 9, said handle being provided with a depending lug 10 which is adapted to coact 10 with the spaced stops 11 formed on the shell 1, as clearly shown in Fig. 4. The plug 1 is provided with a transverse slot or passage 12 and is adapted to register in exhaust position, as shown in Figs. 5 and 6, with the port 13 from the auxiliary reservoir and the exhaust port G'' at the opposite side, while in its other position it establishes communication between the ports 14 and 15 of the branch pipe E leading to the triple valve. 15

It will be understood that the brake cylinder C is connected to the brake gear of conventional type as shown in Figs. 1 and 2, but these parts are not described since they form no part of my invention. 20

In the use of this arrangement of air brake system; when it is desired for one reason or another to cut out a particular train unit or car, or for that matter, when it is desired merely to release the brakes of a car, the 25 valve handle 8 which in the normal position is arranged as shown in Fig. 4 in full lines, in which position the pressure from the train line A passes to the triple valve, and the auxiliary reservoir is closed, is shifted to the dotted line position shown in Fig. 4 so as to 30 cut off the pressure through the branch pipe E to the triple valve and to open the auxiliary reservoir through the branch pipe G to atmosphere. This immediately depletes the 35 pressure in the auxiliary reservoir B and releases the brakes. 40

The advantages of this arrangement are clearly apparent since it is devised with a view to placing of the release valve in the 45 first place at a convenient position of access regardless of whether the car is in motion or not, and in the second place the use of this single valve at the point hereinbefore described permits of the two operations of cutting out the train line and exhausting the reservoir, being accomplished by a simple single movement of the release valve handle. 50

Having thus described my invention, what

I claim as new and desire to secure by Letters Patent, is:—

1. In an air brake system, the combination with a reservoir, a service pipe, and triple valve communicating with said service pipe, of an exhaust line leading from the auxiliary reservoir, and a release valve arranged in said exhaust line and operable to cut out the brake operation on a particular car, and simultaneously exhaust the auxiliary reservoir to thereby release the brakes of said car while service pressure through the service pipe is uninterrupted. 60

2. In an air brake system, the combination with a service pipe, a triple valve in communication therewith, and an auxiliary reservoir communicating with the service pipe through said triple valve, of a release valve arranged between the triple valve and service pipe, and an exhaust line from the auxiliary reservoir to the release valve, said valve being operable to cut off the service pressure to the triple valve and simultaneously exhaust the auxiliary reservoir to atmosphere while service pressure through the service pipe is uninterrupted. 70

3. In an air brake system, the combination with a service pipe, a triple valve, a branch pipe leading from the service pipe to the triple valve, and an auxiliary reservoir, of a release valve arranged in the branch pipe to the triple valve, and a pipe leading from the auxiliary reservoir to said release valve, said valve being constructed to establish communication between the service pipe and the triple valve in one position, and in another position to exhaust the auxiliary reservoir. 80

4. Control means for air brake systems for cars comprising a valve having ports adapted to establish communication between the service pipe and the triple valve when in one position, and other ports adapted to establish communication between the auxiliary reservoir and atmosphere when in another position. 90

5. A release valve for air brake systems comprising a shell having opposite ports for passage of a pressure medium therethrough, said shell also having diametrically opposing exhaust ports, a turn plug disposed within said shell, a screw cap cooperating with the plug to hold the same in position arranged at one side of the shell, and a detachable handle connected to said plug at the opposite side of the shell from the cap aforesaid. 100

In testimony whereof I affix my signature.
JAMES H. DREW.
